Attorney.

UNITED STATES PATENT OFFICE.

RUSSELL HART, OF LOS ANGELES, CALIFORNIA.

MEANS FOR REPRODUCING SOUND FROM GRAPHICAL RECORDS.

Application filed August 13, 1923. Serial No. 657,260.

To all whom it may concern:

Be it known that I, RUSSELL HART, a citizen of the United States, residing at Los Angeles, in the county of Los Angeles and 5 State of California, have invented a new and useful Means for Reproducing Sound from Graphical Records, of which the following is a specification.

I have illustrated in the accompanying 10 drawing and shall describe herewith a preferred form of my invention. I shall also specifically mention certain of its more important objects. I desire to have it understood however that various changes and 15 adaptations may be made without departing from the essence of the invention which is not limited to the form disclosed except as set forth in the appended claims; and that objects other than those specifically mentioned 20 are included within its scope and will appear to those familiar with the art involved.

My invention relates to improvements in 25 means for the reproduction of graphically recorded sound, and particularly to photo-electric means for such reproduction.

Among my more important objects are, first 30 to provide a satisfactory method for utilizing a continuous photographic sound record for sound reproduction; second, to afford facilities for timing and synchronizing the reproduced sound so that it may be used by the methods of cinematography to produce talking motion pictures; third to avoid the 35 use of optical slits and surfaces of any kind in sliding contact with the record; and, fourth, to accomplish the above by means of relatively simple, inexpensive and thoroughly dependable apparatus.

My objects are attained in the manner illustrated in the accompanying drawing, in which—

Figure 1 is a diagram illustrating the manner in which my invention may be used 45 in cinematography for producing talking motion pictures;

Figure 2 is a wiring diagram showing one way in which certain standard electrical devices may be connected up to secure the required amplification of the reproduced 50 sound;

Figure 3 is a front elevation of a photographic sound record on a fragment of motion picture film, and the "sound gate" utilized by me for its reproduction;

Figure 4 is a sectional elevation taken on

the line 4—4 of Fig. 3, looking in the direction of the arrows;

Figure 5 is an enlarged front elevation of a preferred form of photo-electric cell used 60 in connection with my apparatus; and,

Figure 6 is a side elevation of a preferred form of incandescent lamp which I usually employ as a light source.

Similar reference numerals refer to similar parts throughout the several views.

In an application filed Dec. 22, 1922, Serial No. 608,499; and another application filed Apr. 9, 1923, Serial No. 630,870; I disclosed means for producing continuous 70 sound records on photographic films. Such records comprise an opaque area bounded on one side by a straight line corresponding to the axis of abscissæ, and on the other side by a complex curve referred to that axis 75 and corresponding to the sound wave recorded. It is with the reproduction of such records especially that the present invention is concerned.

In the drawings 7 represents a motion picture film with a sound record 8 thereon. The film is mounted on reels 9 and is driven by sprockets 10 at a uniform speed in the manner common in the motion picture art. Between the sprockets the film passes 80 through a "picture gate" 11 and is given an intermittent motion for picture purposes, as by a claw device 12. The film loops 13 permit of this being done without interfering with the continuous motion of the film between the sprockets and the reels. An arc lamp is indicated at 14, a condensing lens group at 15, and projecting lenses at 16. By means of these, and the mechanism previously described, a motion picture may be 95 projected on a screen in the usual manner.

At any convenient point, where the film has a uniform motion, as between a sprocket and its corresponding reel, the "sound gate" 17 is inserted. This constitutes one 100 of the essential elements of my invention and comprises a fixed plate 18, having a hinged cover 19, and two pairs of polished raised runners 20 and 21, between which the film runs. One pair of these runners is 105 shown in Fig. 4 in side elevation, and the position of the two pairs relative to the film, is shown in dotted lines 22 in Fig. 3. Runners 20 are affixed or made integral with plate 18, while runners 21 are movable and are pressed inwardly from cover 19 by screw studs 23 and springs 24; the studs being 110

affixed to their respective runners and freely 5
slidable through holes in the cover 19. This
arrangement permits the film to be accurately
positioned without danger of mar-
ring the pictures and sound record, these
surfaces being spaced by the runners so as
not to come in contact with any part of the
sound gate.

Cover 19 is provided with a small rectangular 10
aperture 25, and there is a similar aperture 26 in the plate immediately behind it. The walls of the latter aperture are preferably polished to render them highly reflecting, and behind this aperture a suitable sensitive 15
photo-electric cell 27 is removably mounted in any convenient manner as by the clips 28.

Any desired type of photo-electric cell, or 20
photo-ionic device, may be employed at 27
provided it is capable of reacting strongly to minute light variations; and provided further that the speed at which it reacts is sufficiently great to properly respond to the requirements of the moving record used. 25
Such cells have been developed and are known in the art. The type of photo-cell here shown comprises a very fine platinum grid 29 filled with selenium or other photo-active material, on a glass "cover plate" 30, and connected by platinized strips 31 to the terminal wires 32. A cup 33 containing anhydrous calcium chloride, or a similar substance, is cemented upon the back of the cover plate, enclosing the photo-active material and keeping it dry. 35

The preferred form of light source for sound reproduction herein illustrated was described and claimed by me in the application filed Apr. 9, 1923, referred to above and 40
comprises a luminous filament 34 attached at one end to a fixed terminal 35, and at the other end to a resilient terminal 36 capable of maintaining the filament in tension throughout the range of its temperature variations. 45
The filament thus is always rectilinear. The tubular lamp 37, in which the filament is mounted, is supported by a clamp 38 adapted for adjusting the filament at the proper vertical angle in a plane parallel to 50
film. An objective lens group 39 is interposed between the lamp and the film, and means (not shown) are provided for focusing this lens group to cast a very sharp de-magnified image of the filament upon the 55
sound record of the film.

The rays of light falling upon the sound record in the manner just described will constitute an exceedingly narrow transverse band and be variably eclipsed by the opacity 60
of the record in conformity with the instantaneous values of the ordinates of the sound curve. The un-eclipsed rays will pass through the film and fall upon the active surface of the photo-electric cell and proportionally 65
vary its resistance. Consequently,

if a constant electro-motive force is applied to the terminals of the cell, the current in the cell circuit will be modulated in conformity to the sound record. This modulated current is then utilized for telephonic 70
reproduction of the original sound.

There are various ways known to the art for amplifying the modulated current to make it available for loud speaking devices. 75
One method of doing this is illustrated diagrammatically in Fig. 2, wherein standard electrical devices are conventionally shown. In this diagram a loud speaking instrument is indicated at 40.

Reference was made above to synchronizing the sound reproduction and the operation of a picture film so that the invention could be employed for producing talking motion pictures. Inasmuch as the motion pictures are intermittently projected from the film, and the sound record must be continuously reproduced, it is impractical to make use of the same portion of the film for these two purposes simultaneously. The sound record therefore is placed upon 90
the film a definite distance either in advance or behind the corresponding picture, and the sound gate is similarly located, so as to operate in synchronism with the projected pictures. 95

The purpose of polishing the interior surfaces of orifice 26 previously mentioned is to render them reflecting, and non-absorbent of light rays, so far as this is possible. In this way the light that passes the sound record may be utilized to the fullest possible extent for producing the desired effect upon the photo-electric cell. 100

I desire to point out particularly that the arrangement and construction of my apparatus makes it entirely unnecessary to employ an optical slit in contact with the recorded film, and that the surface of the record is not subjected to sliding contact in any portion of my device. There is no 105
danger from abrasion from this source therefore, and the life of the film is greatly lengthened in consequence. 110

I also wish to call attention to the fact that my invention requires a relatively small 115
amount of energy for sound reproducing purposes. This is important and advantageous for several reasons, in addition to the reduced cost of energy consumption. For instance the small energy requirement 120
permits of the use of a battery for lighting the filament 34, and this in turn results in a perfectly steady reproducing light and absolutely eliminates the effect of "stray noise" in the reproduction due to audio-frequency variations in the light source. The effect of alternating current "hum" is 125
completely avoided in this manner. Again, the small energy requirement makes it practically impossible to overheat the film, and 130

the use of such devices as automatic light gates to prevent burning the film is superfluous.

I claim as my invention:

- 5 1. Apparatus for sound reproduction comprising; a uniformly movable film having a sound record thereon adapted for continuously intercepting light rays in varying degrees; a tenuous illuminable filament 10 in tension; an intermediate lens adapted for focusing an image of said filament upon said record transversely to its direction of motion; and means for transforming the light rays that pass through the record into 15 sound waves.
2. Apparatus for sound reproduction comprising; a uniformly movable film having a sound record thereon adapted for continuously intercepting light rays in varying degrees; a linear light source of great 20 tenuity; an intermediate lens adapted for focusing an image of said source upon said record; means for angularly adjusting the position of said image with respect to said

record; and means for transforming the 25 light rays that pass through the record into sound waves.

3. Apparatus for sound reproduction comprising; a movable film having a continuous sound record of substantially uniform translucency and varying width thereon; a linear light source; means for projecting an image of said source perpendicularly upon said record; means for angularly adjusting the position of said image with respect to the direction of motion of said record; a photo-electric cell behind said record adjacent thereto adapted for modulating an electric current proportionally to the amount of light that passes 40 through the record; and means for utilizing said modulated current for the reproduction of sound.

4. In apparatus of the character described, in combination, a photo-electric cell; 45 a spaced optical film; and an intermediate aperture having highly reflecting walls.

RUSSELL HART.
